UNITED STATES PATENT OFFICE.

THOMAS A. KILLMAN, OF NASHVILLE, TENNESSEE.

CAN OPENER.

Application filed January 8, 1925. Serial No. 1,823.

To all whom it may concern:

Be it known that I, THOMAS A. KILLMAN, a citizen of the United States, residing at Nashville, in the county of Davidson and State of Tennessee, have invented certain new and useful Improvements in Can Openers, of which the following is a specification.

This invention relates to can openers and more particularly to that type of can opener including a rotary cutting disk and a rotating feeding device by means of which the can is shifted for engagement with the cutting disk.

15 An important object of this invention is to provide a device of this character in which the cutting disk is adapted to remove the top of the can by severing such top at a point adjacent its outer circumference as differentiated from those can openers removing the can top by severing the side wall of the can immediately adjacent the top. Can openers of the latter type are faulty in that either the can opener must 25 be rotated bodily about the can while the can is seated upon a support or must be rotated upon a support with relation to the can due to the fact that no means are provided for holding the can once the top 30 is severed. Accordingly a more specific object of the invention is to provide means for holding the can after the top is severed.

A further object of the invention is the provision of a can opener of the character 35 described and of such construction that the can is held level at all times so that the contents thereof will not be spilled as the can top is severed or removed and in which it is unnecessary for the operator to support 40 the can in any manner during the cutting operation, or after such cutting operation is completed until it is desired to remove the can from the can opener.

45 A still further object of the invention is the provision of a can opener including a cutting device and a rotating feeding device, one of said elements being adjustable toward the other to force the cutter through the material of the can and in which means are provided for locking the cutter in this engaged position, thus eliminating the necessity of holding a lever or other means for maintaining the engagement of the cutter.

50 A still further object of the invention is to provide a device of this character in which the movement of the elements toward

one another is of such character that the can is not rotated during this movement, thereby materially reducing the pressure which is required to force the can to the can 60 opener since this pressure is all applied at a single point on the can and not distributed along a portion of the circumference due to the shifting of the can.

These and other objects I attain by the 65 construction shown in the accompanying drawings, wherein for the purpose of illustration is shown a preferred embodiment of my invention and wherein:—

Figure 1 is a side elevation partially in 70 section of a can opener constructed in accordance with my invention, a can being shown in position and the cutter and feeding rollers being shown in operative relation;

75 Figure 2 is a rear elevation of the can opener, the feed roller operating handle being removed and the parts being shown in the operative position;

Figure 3 is a similar view of the parts in 80 the inoperative or can receiving position;

Figure 4 is a sectional view showing the 85 relative positions of the cutter and feed roller; and

Figure 5 is a detailed sectional view showing the mounting of the cutter.

Referring now more particularly to the drawings, the numeral 10 indicates a vertical support, preferably having means at its lower end, as indicated at 11, whereby it 90 may be clamped to a table or suitable bracket. The upper end of the support has an inclined extension 12 having an opening 13 formed therethrough through which is directed a bearing 14 having a flange 15 through which 95 are directed securing elements 16 attaching the bearing to the extension at the sides of the opening. Through this bearing is directed a spindle 17 to one end of which is secured a cutter disk 18, one face of which 100 is bevelled to provide the sharpened cutting edge 19. The angle of the extension 12 is such that this bevelled face is substantially vertically disposed and parallels the upper end of the support 10 in spaced relation 105 thereto. The cutting edge is thus thrown at an angle to the vertical support for a purpose hereinafter to appear. At opposite sides of the extension 12, the upper end of the support has horizontally directed arms 110 20 arranged at opposite sides of the cutter 18.

2

Vertically below the opening 13, the vertical support 10 is formed with a vertically extending slot 21. Into this slot extends one end of a bearing 22 carried by a link 23. The bearing 22 is similar to the bearing 14 hereinbefore described having a flange 24 attached to the link 23 at the sides of an opening 25 formed through the link. The slot is of a width equal to the outside diameter of the bearing. Through the bearing is directed a spindle 26 to one end of which is secured a knurled disk 27 confronting the vertical support and in spaced relation thereto and at the opposite end of which is secured a handle H whereby the spindle 26 may be rotated. When the link is so arranged that the bearing is at the upper end of the vertical slot, the lower edge of the cutter disk and the upper edge of the knurled disk overlap, the outer face of the knurled disk being in spaced relation to the adjacent bevelled face of the cutter 18 and paralleling the same, the space between these adjacent faces is slightly greater than the size and thickness of tin ordinarily employed in the construction of storage cans. When the link 23 is so arranged that the bearing is at the lower end of the slot, the upper edge of the knurled disk is vertically spaced below the lower edge of the cutter disk a distance such that the rim R of a can C may be inserted therebetween.

An operating lever 28 is provided, the upper end of which has secured thereto a disk 29 rotatably fitting an opening 30 formed in the link. The disk is of the same or slightly greater thickness than the thickness of the link and is pivoted together with the handle to the vertical support by a pivot 31 engaging the disk eccentrically thereof. The engagement of the pivot with the disk and the length of the lever 28 are such that the link, when the handle is moved from the position A of Figure 3 to the position B of Figure 2, the link is vertically shifted and moves the bearing from the lower to the upper end of the slot thereof. Attention is directed to the fact that the cam or eccentric 29 is in effect one link of a toggle mechanism of which the link 23 forms the second link. To the link or eccentric 29 is rigidly connected the operating lever 28 of this toggle mechanism. While an eccentric and link have been employed, it will be obvious that the substitution of an actual link for this eccentric is well within the scope of the present invention.

At the same time, the point of pivot of the link upon the disk will be moved from one side of a line connecting the axial centers of the pivot 31 and spindle 26 to the opposite side thereof. When in the position B, the lower end of the handle comes into engagement with the upper surface of the attaching bracket 11 so that its move- ment in the direction of the arrow is positively limited. It will be obvious that any strain placed upon the spindle tending to force the same downwardly or away from the cutter 18 will be directed upon a longitudinal axis of the link and since this link is applying its pressure in a direction such that if it is moved, the handle 28 must move in the direction of the arrow when the handle is in the position B that the knurled roller is locked against any movement whatever with relation to the support or with relation to the cutter.

It will be obvious that while I have employed a disk as a means of providing this latching toggle movement that any suitable type of latching toggle might be employed with equal facility although the disk provides the most solid and rigid form of attachment known to me and is preferred by me. It will also be obvious that since the handle is engaged with the upper surface of the attaching bracket 11 during the period when the can is locked in the can opener and the cutting is being performed, a great deal of the stress is removed from the pivot 31 and supported from the handle, thus preventing too rapid wear and deterioration of this pivot.

In the use of the device, the lever is first moved to the position A and at this time, the cutter and knurled wheel are separated and the bit of rim R of the can is inserted between the cutter and knurled wheel. The handle is then moved to the position B and due to the great leverage, substantially a camming, but little force is required to force the cutter through the tin of the top. Then the crank 11, which is connected to the feed roller 27, is turned, and due to the fact that the knurled feed roller engages the lower edge of the rim R, the can will be caused to rotate, thus feeding the can to the cutter which cuts or severs the head on a line close up against the inside wall of the can, thus leaving no portion of the head projecting inward which would interfere with the removal of the contents of the can. The crank is turned until the can has made a complete revolution which completes the operation of cutting the head out. Then the cam lever 28 is raised which separates the cutter and feed roller which releases the can so it can be removed from the machine. During the operation the can is locked in the machine and held suspended by it so that it does not need to be held by the operator. Attention is directed to the fact that the knurled wheel moves toward the cutter in a straight line. This knurled wheel has a flat outer face against which the wall of the can may rest and since the distance between adjacent faces of the feed roller and cutter is but substantially equal to the thickness of the wall of the can, it will be obvious that

the can would only be capable of a very slight tilting movement forward and away from the support and this tilting movement would be such that none of the liquid contents of the can would be spilled. The arms 20 hereinbefore referred to act to prevent tilting of the axis of the can in a plane parallel to the support, the can upon inclination thereof in such a plane bringing the upper edge of its rim into contact with one of the other of the arms so that this movement is checked. This is an important feature of my construction in that it overcomes the tendency to oscillation or tilting caused by pulling of the feed roller and the resistance of the cutter. This tilting, if permitted, will not only result in spilling of the contents but will cause the cutter to engage in the rim of the can which would check the operation of the can opener and dull the cutter. Attention is directed to the fact that by the use of a device of this character, the top may be entirely or partially severed as is desired and that the can after the severing of the top will be supported by its rim R and cannot escape therefrom for the reason that the inner face of this rim engages against the adjacent inclined face of the cutter 18. Attention is further directed to the fact that the inclination of the cutter causes the same to lean or tilt toward the center of the can so that it will "track" around the can properly. Where these cutters are perpendicularly set, there is a tendency of the cutter to cut across the rim of the can whereas if inclined at the proper angle, it will engage only the head of the can without cutting into the rim. It will be obvious that any tendency to cut into the rim causes a heavy resistance and will tend to rapidly dull the cutter. While, of course, a perpendicularly set cutter may be caused to engage the top of the can in sufficiently spaced relation to the rim to avoid this cutting into the rim, it is difficult to keep such cutters properly aligned and furthermore, an inwardly extending flange is left upon the top of the can rendering removal of the contents difficult.

Since obviously the structure hereinbefore set forth is capable of a certain range of change and modification without materially departing from the spirit of my invention, I accordingly do not limit myself to such specific structure except as herein-after claimed.

I claim:—

1. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping
2. In a can opener, a vertical support, a cutting roller rotatably supported at the upper end of the support, a knurled feeding roller carried by and vertically shiftable upon the support toward and away from the cutting roller, the can upon inclination thereof in such a plane bringing the upper edge of its rim into contact with one of the other of the arms so that this movement is checked.
3. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from the cutting roller.
4. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from the cutting roller, including a lever movable in one direction to shift the feeding roller toward the cutting roller, means limiting the movement of the lever in such direction when the feeding roller is at the upper limit of its travel, said toggle mechanism being such that pressure applied to separate the feeding and cutting rollers, when in cutting position, tends to move said lever in said direction.
5. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from the cutting roller, latching when the cutting roller is at the upper limit of its travel.
6. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from the cutting roller, including a lever pivoted to the support, a link from which the feeding roller is supported, a pivotal connection between the lever and the link at a point spaced from the pivot of the lever.
7. In a can opener, a vertical support, a cutting roller rotatably supported at the upper limit of its movement overlapping

- 4
- upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from the cutting roller, including a lever pivoted to the support, a link from which the feeding roller is supported, a pivotal connection between the lever and the link at a point spaced from the pivot of the lever, said pivotal connection moving from a point at one side of a line connecting the axis of rotation of the feeding roller and the pivot to the opposite side thereof as the lever is moved to shift the link and feeding roller from one limit of its movement to the opposite limit thereof.
6. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from the cutting roller, including a lever pivoted to the support, a link from which the feeding roller is supported, a pivotal connection between the lever and the link at a point spaced from the pivot of the lever, said pivotal connection moving from a point at one side of a line connecting the axis of rotation of the feeding roller and the pivot to the opposite side thereof as the lever is moved to shift the link and feeding roller from one limit of its movement to the opposite limit thereof, and means limiting the movement of the lever in a direction shifting the feeding roller toward the cutting roller when the feeding roller is at the upper limit of its movement.
7. In a can opener, a vertical support, a cutting roller rotatably supported at the upper end of the support, a knurled feeding roller carried by and vertically shiftable upon the support toward and away from the cutting roller, said feeding roller at the upper limit of its movement overlapping the cutting roller and at the lower limit of its movement being spaced therefrom a distance permitting the insertion of the can rim therebetween, means for rotating the feeding roller and toggle mechanism for moving the feeding roller toward and away from
- the cutting roller, including a lever pivoted to said support, a link having a bearing operating in the slot of the support, a spindle rotatable in said bearing and by which the feeding roller is carried, a handle engaged with the spindle for rotating the same and a disk secured to the lever eccentrically of the pivot thereof and engaged in an opening formed in said link.
8. In a can opener, a vertical support, a cutting roller rotatable upon the support, a feeding roller for engagement with the under surface of a can rim carried by the support and adjustably shiftable in a straight line toward and away from the axis of the cutting roller, means for rotating the feeding roller and means for shifting the feeding roller.
9. In a can opener, a vertical support, a cutting roller rotatable upon the support, a feeding roller for engagement with the under surface of a can rim carried by the support and adjustably shiftable in a straight line toward and away from the axis of the cutting roller, means for rotating the feeding roller and means for shifting the feeding roller latching the feeding roller when said feeding and cutting rollers are in operative position.
10. In a can opener, a vertical support, a cutting roller rotatable upon the support, a feeding roller for engagement with the under surface of a can rim carried by the support and adjustably shiftable in a straight line toward and away from the axis of the cutting roller, means for rotating the feeding roller and means for shifting the feeding roller, the feeding and cutting rollers when in operative relation having opposed faces, the opposed face of the cutting roller being at an inclination to the cutting edge thereof.
11. In a can opener, a vertical support, a cutting roller rotatable upon the support, a feeding roller for engagement with the under surface of a can rim carried by the support and adjustably shiftable in a straight line toward and away from the axis of the cutting roller, means for rotating the feeding roller, and means for shifting the feeding roller, said feeding and cutting rollers when in operative relation having spaced opposed faces, the space between said faces being greater than the thickness of a can wall below the rim thereof and less than the thickness of the wall at the rim.
12. In a can opener, a vertical support, a cutting roller rotatable upon the support, a feeding roller for engagement with the under surface of a can rim carried by the support and adjustably shiftable in a straight line toward and away from the axis of the cutting roller, means for rotating the feeding roller, and means for shifting the feeding roller, said feeding

- and cutting rollers when in operative relation having spaced opposed faces, the opposed face of the cutter roller being at an 5
inclination to the cutting edge thereof, the
space between said faces being greater than
the thickness of a can wall below the rim
thereof and less than the thickness of the
wall at the rim.
13. In a can opener, a vertical support, a
10 cutting roller rotatable upon the support, a
feeding roller for engagement with the under
surface of a can rim carried by the support
and adjustably shiftable in a straight line to-
ward and away from the axis of the cutting
15 roller, means for rotating the feeding roller,
means for shifting the feeding roller and
means carried by and extending outwardly
from the support and overlying the upper
surface of the engaged can outwardly of the
20 cutting roller and at opposite sides thereof
for preventing oscillation of the can while
engaged between the cutting and feeding
rollers.
14. In a can opener, a vertical support, a
25 cutting roller rotatable upon the support,
a feeding roller for engagement with the under
surface of a can rim carried by the sup-
port and adjustably shiftable in a straight
line toward and away from the axis of the
30 cutting roller, means for rotating the feed-
ing roller, and means for shifting the feed-
ing roller, a pair of arms carried by said
vertical support and extending outwardly at
35 opposite sides of the cutting roller and
adapted to overly a can top to prevent oscil-
lation of the can during the cutting opera-
tion.
15. In a can opener, means for guiding
40 and rotating a can in vertical position and
a cutting roller engaging the top of a can
engaged by said means and having its cutting
edge in a plane at an angle to the axis of the
can and the portion of its cutting edge which
45 uppermost being most nearly adjacent such
axis, said means for guiding and rotating
the can including a feeding roller having its
periphery knurled for engagement with the
under surface of a can rim and its outer face
50 plane, the lowermost portion of the cutting
edge of the cutting roller being spaced from
such outer face a distance substantially
equal to the thickness of a can wall.
16. In a can opener, means for guiding
55 and rotating a can in vertical position and
a cutting roller engaging the top of a can
engaged by said means and having its cutting
edge in a plane at an angle to the axis
of the can and the portion of its cutting edge
60 which is uppermost being most nearly adja-
cent such axis, said means for guiding and
rotating the can including a feeding roller
having its periphery knurled for engage-
ment with the under surface of a can rim and
65 its outer face plane, the lowermost portion
of the cutting edge of the cutting roller be-
ing spaced from such outer face a distance
substantially equal to the thickness of a can
wall, whereby oscillation of the can toward
70 and away from the feeding roller is pre-
vented and means engaging the can for pre-
venting oscillation of the can in a plane par-
alleling the base of the feeding roller.
17. In a can opener, means for guiding
75 and rotating a can in vertical position and
a cutting roller engaging the top of a can
engaged by said means and having its cutting
edge in a plane at an angle to the axis of the
can and the portion of its cutting edge
80 which is uppermost being most nearly adja-
cent such axis, said means for guiding and
rotating the can including a feeding roller
having its periphery knurled for engage-
ment with the under surface of a can rim and
85 its outer face plane, the lowermost portion
of the cutting edge of the cutting roller
being spaced from such outer face a distance
substantially equal to the thickness of a can
wall, whereby oscillation of the can toward
90 and away from the feeding roller is pre-
vented and means engaging the can for prevent-
ing oscillation of the can in a plane par-
alleling the base of the feeding roller, includ-
ing pair of arms carried by the support and
95 extending at opposite sides of the cutting
roller and overlying the rim of the can in
close proximity thereto.

In testimony whereof I affix my signature.
THOMAS A. KILLMAN.
